(57) **CLAIM**

The ornamental design for a gun case, as shown and described.

DESCRIPTION

FIG. 1 is a front and top perspective view of a first embodiment of a gun case, showing my new design; FIG. 2 is a rear and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a front and top perspective view of a second embodiment of the gun case; and, FIG. 10 is a rear and bottom perspective view thereof. The broken lines in the figures illustrate portions of the gun case that form no part of the claimed design.
